J. M. DAPRON

AIR ENGINE

Filed April 21, 1924

INVENTOR JOSEPH M. DAPRON,
by James L. Hopkins, Attorney.

UNITED STATES PATENT OFFICE.

JOSEPH M. DAPRON, OF ST. LOUIS, MISSOURI, ASSIGNOR TO NATIONAL PNEUMATIC COMPANY, OF NEW YORK, N. Y., A CORPORATION OF WEST VIRGINIA.

AIR ENGINE.

Application filed April 21, 1924. Serial No. 707,875.

My invention relates to improvements in air engines of the double-cylinder type, wherein each cylinder is provided with a piston and those pistons are connected by 5 a single piston-rod; the cylinder-head of each of said cylinders having but a single diametrical port.

The present invention relates to a double-piston air-engine in which the advancing 10 piston initially moves against atmospheric pressure only (the cylinder-space before it having been exhausted of all compression by being vented to atmosphere before the advance stroke commences), and the valve- 15 stem being seated after the advance stroke has continued a predetermined distance (approximately half the total length of the stroke in the illustrated engine) closes the exhaust port; from which moment the continued advance of the piston proceeds to manufacture compressed air to serve as a resistance cushion to check the movement of 20 said advancing piston.

Drawings.

In the drawings—

Fig. 1 is a longitudinal mid-sectional view of an engine embodying my invention.

Fig. 2 is an inverted plan view of the 30 same.

Description.

The opposed cylinders 3 and 4 are provided with the cylinder-heads 5 and 6 respectively, and are connected in alinement by the central housing 7 through which the shaft 8 is suitably journaled.

The pistons A and B are mounted in the cylinders 3 and 4 respectively and are 40 mounted on the ends of the piston-rod C which serves to connect them rigidly together, and which midway its length is apertured at 9 to receive the roller 10 on the free end of the crank-arm 11.

Each of the cylinder-heads 5 and 6 has a central port 12, and each of the pistons A and B has a central bore 13 to receive a valve-stem 14 having a conoidal outer terminal 15.

The piston-rod C is provided with longitudinal bores 16, restricted at 17 to form a seat and bearing for the thimble 18, said thimble 18 receiving the inner end of the sleeve 19 in which the valve-stem 14 is yield-

ingly and adjustably mounted by means of 55 the spring 20 and screw plug 21.

The sleeve 19 has at its base the shoulder 22 against which the coiled spring 23 is mounted surrounding said sleeve 19 and with its inner terminal abutting against the 60 mouth of the thimble 18.

The roller 10 is mounted between the closed ends of the thimbles 18—18 as shown in Fig. 1.

Each of the pistons A and B is constructed as illustrated in the sectional view of the piston A in Fig. 1. The outer face of the piston A is provided with the dished washer 24, surrounding the threaded nipple 25 and held in place by the nut 26. The inner face 70 of the piston A is provided with a concentric dovetailed groove 27, in which is imbedded an annulus 28 of rubber or the like, the function of which annulus 28 is to impact upon the inner flange 29 of the port 30, and thereby seal the cylinder 3 at the end of the inward stroke of the piston A. When the cylinder 3 is so sealed, the roller 10 will be cushioned between the closed ends of the thimbles 18—18, said thimbles 18—18 being 80 balanced by the pressure within the cylinders 3 and 4, the piston-rod C being rigidly held by the contact of the piston A with its flanged seat 29.

Mode of operation.

The engine being in the position shown in Fig. 1 the cylinder 4 has been exhausted to atmosphere through its port 12.

Compressed air is then admitted to the 90 cylinder 3 through its port 12, driving the cylinders A and B to the right, until the terminal 15 of the valve-stem 14 of the piston B seats in and closes the port 12 of the cylinder 4. The rapidity of the movement 95 thus far described will correspond with the pressure of the air introduced to the cylinder 3, and that speed must be diminished by an opposing pressure in the cylinder 4, which is built up in the further progress toward 100 the end of its outward stroke of the piston B by the cooperation of the valve-stem 14 and the thimble 18 (due to their respective spring-mountings above described), with the 105 roller 10.

The described mechanism may be varied in construction in many respects, as it is merely the single form exhibited by me in

response to the statutory requirement, without departing from my invention as defined in the following claims.

In the mode of operation of the engine of my invention, however, each of the double cylinders must be provided with a port 12, or its equivalent, in its outer head through which the cylinder may be readily and quickly exhausted to atmosphere; and the inner head 31 of each cylinder must have a relatively large port 30, or its equivalent, to admit air at atmospheric pressure freely into its communicating cylinder at all times save when that cylinder is sealed by the contact of the inner face of the piston (A or B) with the inner mouth of said port 30.

Claims.

I claim—

20 1. In an air engine in combination, two
aligned cylinders; a central housing connecting
said cylinders; a pair of pistons mounted
one in each of said cylinders; a piston-rod
connecting said pistons; two cylinder-heads,
25 one mounted on the outer end of each of
said cylinders, and each having a central
port; a restricted longitudinal bore in each
end of said piston-rod; a thimble seated in
30 the inner end of each of said bores; a crank
journaled in said housing having a roller
thereon, said roller projecting between said
thimbles; a sleeve mounted in each of said
bores and yieldingly and slidably mounted
35 within one of said thimbles; and a valve-
stem yieldingly mounted in each of said
sleeves, each valve stem being adapted to
seat in the port on the cylinder head of the
cylinder in which it moves before the com-
40 pletion of the stroke of the piston on which
it is mounted.

2. In an air engine in combination, two
aligned cylinders; a central housing connect-

2. In an air engine in combination, two aligned cylinders; a central housing connect-

ing said cylinders; a pair of pistons mounted one in each of said cylinders; a piston-rod connecting said pistons; two cylinder-heads, 45 one mounted on the outer end of each of said cylinders, and each having a central port; a restricted longitudinal bore in each end of said piston-rod; a thimble seated in the inner end of each of said bores; a crank 50 journaled in said housing having a roller thereon, said roller projecting between said thimbles; a sleeve mounted in each of said bores and yieldingly and slidably mounted within one of said thimbles; and a valve- 55 stem having a conoidal outer terminal arranged to be seated in the port of the adjacent cylinder head and yieldingly mounted in each of said sleeves.

3. In an air engine in combination, two aligned cylinders; a central housing connecting said cylinders; a pair of pistons mounted one in each of said cylinders; a piston-rod connecting said pistons; two cylinder-heads, one mounted on the outer end of each of said cylinders, and each having a central port; a restricted longitudinal bore in each end of said piston-rod; a thimble seated in the inner end of each of said bores; a sleeve mounted in each of said bores and yieldingly and slidably mounted within one of said thimbles; a valve-stem yieldingly mounted in each of said sleeves; a crank arm mounted in said housing; and a roller carried thereby, said roller being mounted between the inner ends of said thimbles, each valve stem being adapted to seat in the port on the cylinder head of the cylinder in which it moves before the completion of the stroke of the piston on which it is mounted.

In testimony whereof I have hereunto affixed my signature.

JOSEPH M. DAPRON
